Attorney

UNITED STATES PATENT OFFICE.

CARLON F. HEPLER, OF SENECA, PENNSYLVANIA.

FASTENING MEANS.

Application filed October 3, 1928. Serial No. 309,974.

This invention relates to an improved metal rail tie, and novel means for fastening the rail thereto.

In carrying out the invention, I propose to provide a metal tie in the form of an I beam and to utilize a pair of duplicate fastening devices for the rails which are slidably mounted on the top flange of the tie, each device being especially designed to accomplish the desired result in a practical and efficient manner.

The particular details of the devices and as well as their specific cooperation with the tie will become more readily apparent from the following drawings.

In the drawings:—

Figure 1 is a top plan view of a rail tie constructed in accordance with the invention, showing the improved fastening device attached thereto.

Fig. 2 is an enlarged transverse section through the tie, taken approximately upon the plane of the line 2—2 of Fig. 1.

Fig. 3 is an exaggerated cross sectional view through the rail, taken approximately on the plane of the line 3—3 of Fig. 1.

Fig. 4 is a longitudinal section through the major part of one of the improved fastening devices.

Fig. 5 is a perspective view of a complementary clamping plate, and

Fig. 6 is an elevational view of one of the retaining bolts.

In the drawings, the rail is designated by the reference character 7, the tie is indicated at 8, and the fastening means is indicated as composed of a slideable part 9 and a clamping part or plate 10.

As before stated, the tie 8 is in the form of a metal I-beam of appropriate proportions, it being understood that this is to take the place of the customary wooden, concrete and other forms of metallic ties. The clamping device at each end is the same in construction, and a description of one will suffice for both. As already indicated, the principal part is that part designated generally by the reference numeral 9. It embodies a plate which rests slidably upon the top of the upper flange of the tie.

This plate includes a relatively thick central portion having a flat surface 11 forming a seat for reception of the base flange of the rail. At the opposite ends of this flat part, we find upstanding transversely extending ribs functioning as abutments 12. These

prevent shifting of the rail on the plate. Beyond the abutments are downwardly inclined and tapered end extensions 13, which bear in a yieldable manner upon the top flange of the tie.

On the opposite longitudinal sides of the device are hooked members, each of which includes a curved web portion 14 joined integrally with the plate, and also a complementary bottom plate 15, and the bottom plate has a raised central fulcrum 16 and the end portions thereof cooperate with the end extensions 13 of the top plate in providing a desirable resilient clamping action.

Obviously, bolts extend up through the tapered end portions of the bottom plates and through registering openings in the top plates, whereby to fasten the device in the top flange of the tie and to afford a desirable cushion-like action for the rails.

It will be noted that the abutments 12 prevent the base flange of the rail from coming into engagement with the threaded shank portion of the bolt. Also, the bolts are located at the opposite ends of these abutments.

Moreover, the shank portion of the bolt is square in cross section, and smooth as designated at 17 in Fig. 6. The bolt also includes a screw threaded portion 18 to accommodate the retaining nut 19.

The threaded ends and retaining nuts cooperate with the clamping plates 10. There are two of these plates, one on each side of the rail. The plate portion 20 overlies the base flange of the rail and this is provided with holes 21 for passage of the retaining bolts. It also has extensions 22 at the opposite ends which are bent up as shown in Fig. 2, to prevent accidental displacement of the nut. The bending action is produced through the medium of a sledge hammer or the like, after the nuts are applied.

The plate 10 also includes a rolled or curved edge portion 23 which rests upon the abutment as shown in Fig. 2. This provides a further resilient feature in the clamping action. It is noted that in order to place the fastening device in position for securing the rail to the tie, the device must be slipped over the end of the top flange and moved inwardly until it reaches the proper point. Then the rail is seated on the flat portion of the part 9 between the abutments 12 as explained, whereupon the bolts are passed upwardly through the aligned holes in the parts

9 and 10 and as well as through the openings in the top flange of the tie. When the retaining nuts are placed in position, to bind the portions 13 and 16, against the top flange, 5 simultaneously, the plate 10 is clamped firmly down upon the base flange of the rail. However, as before stated, the clamping action is of a resilient nature, yet sturdy and dependable. It is thought that the advantages, construction, and features of this sort of construction, will be quite clear to persons skilled in the art to which the invention relates. Therefore, a more lengthy description is regarded unnecessary.

10 15 Minor changes in shape, size, and arrangement of parts coming within the field of invention claimed, may be resorted to in actual practice if desired.

Having thus described my invention, what 20 I claim as new is:—

1. In a rail fastening and clamping device of the class described, comprising a plate having a flat central portion with upstanding abutments and downwardly tapered and inclined end extensions, together with a longitudinal hooked portion for engaging a rail tie.

2. In a rail fastening and clamping device

of the class described, comprising a plate having a flat central portion with upstanding abutments and downwardly tapered and inclined end extensions, a longitudinal hooked portion for engaging a rail tie, and a pair of clamping plates having rolled edge portions engageable with said abutments. 30 35

3. A rail fastening device of the class described comprising, a multiple part structure wherein one of said parts comprises a rail base plate having a relatively thick central portion with a flat seat at the ends of which are upstanding abutments, and beyond which are downwardly inclined and tapered extensions, and a pair of lower plate portions joined to the longitudinal edges of the rail base plate by curved webs, said lower plate portions having centrally disposed fulcrums. 40 45

4. As a new product of manufacture, a rail fastening device embodying a pair of rail clamping plates each having bolt holes and bendable extensions adapted to function as nut retainers, each plate being formed along one edge with a longitudinal resilient rolled portion. 50

In testimony whereof I affix my signature.
CARMON F. HEPLER.
